UNITED STATES PATENT OFFICE.

JOHN L. WHITTAKER, OF WINTHROP, MASSACHUSETTS, ASSIGNOR TO MILLER TROLLEY SHOE COMPANY, OF BOSTON, MASSACHUSETTS, A CORPORATION OF MASSACHUSETTS.

TROLLEY SHOE.

Application filed January 26, 1922. Serial No. 531,994.

To all whom it may concern:

Be it known that I, JOHN L. WHITTAKER, a citizen of the United States, and a resident of Winthrop, in the county of Suffolk and 5 State of Massachusetts, have invented an Improvement in Trolley Shoes, of which the following description, in connection with the accompanying drawings, is a specification, like characters on the drawings representing like parts.

This invention relates to overhead current collectors for electric trolley systems and the object is more particularly to provide an improved device of the sliding contact type.

My invention will best be understood by reference to the following description of the illustrative embodiment thereof shown by way of example in the accompanying drawings, wherein:

Fig. 1 is a side elevation of a trolley shoe embodying my invention positioned in contact with the trolley wire;

Fig. 2 is a section on the line 2—2 of Fig. 25 1; and

Figs. 3 and 4 are respectively a plan and an edge view of an element utilized in the construction.

Referring to Figs. 1 and 2 of the drawings, I there show a suitable harp 5 provided with the arms 7 between which extends the pintle pin 9 on which is pivoted the contact member or shoe proper 11. This shoe 11 may be formed from a single forging 30 of suitably prepared steel and herein is shown as consisting of the grooved tread part 13 having a depending web 15 through which passes the pintle 9, pivotally supporting the shoe. The grooved tread member preferably, as best shown in Fig. 2, overhangs the arms of the harp. The tread member provides a substantially flat bottomed groove of considerable extent for co-operation with the trolley wire *w*, the groove being flanked by flanges which, as indicated by the dotted lines in Fig. 1, conveniently taper toward the front of the shoe and the bottom of the groove merges into the outer face of a depending bill portion 17 which 40 extends as shown down between the arms of the harp when the shoe is in the horizontal position indicated in Fig. 1. The bill 17 serves in a certain measure as a guard to prevent a wire from entering between the arms of the harp or catching

under the shoe. It furthermore provides for the convenient attachment of a connecting bond 19 preferably consisting of a number of copper cables secured to the end of the bill 17 and also connected at 21 to the 50 harp.

The shoe shown has a swinging movement due to its mounting which permits it to adapt itself to various conditions of use, for example to compensate for the varying angularity of the trolley pole as the height of the trolley wire varies in service. In accordance with my invention, however, this swinging movement is not unrestrained but is permitted to take place only in the way of 65 adjustment when the shoe is acted upon by substantial outside forces. Thus, considering the shoe and its mounting as a whole, I preferably provide means in the nature of a brake restraining the movement of the shoe 70 so that if the shoe were tilted to any position it would normally remain in that position until displaced by some exterior force. In particular I provide for neutralizing the overbalancing effect of the depending bill 75 17 and of such portion of the shoe as extends forwardly of the pintle 9 which as shown in the drawings is placed near the rear end of the shoe 11.

Such braking action is conveniently effected by means of a spring washer 23 (see Figs. 2, 3 and 4) interposed between the web 15 of the shoe and one of the arms 7 of the harp. This washer may be provided with the customary burred ends 25 (see Fig. 4) 80 causing it to bite the adjacent parts. The use of this washer has the effect of a brake on the movement of the shoe which can no longer swing freely but is displaced only when some considerable force from the outside 85 acts upon it.

This dampening of the action of the shoe provides for a more steady action thereof and prevents a chattering on the trolley wire. The shoe is pressed with an even constant pressure against the wire and is not subject to movement by relatively small forces which might lead to displacing it. As an instance of the advantages of mounting the shoe in this manner I may cite the 90 case when the shoe has jumped the wire and the trolley pole comes in contact with a cross wire as the car coasts along. As the shoe leaves the wire the elevating gear at the base of the trolley pole swings the latter up 95

wardly and as the car advances the pole is brought with considerable force against adjacent cross wires or suspending wires. The cross wire slides up along the pole and over the face of the shoe. A loosely pivoted shoe may oscillate violently under the shock of such contact and the cross wire as it draws upwardly over the face of the harp is likely to meet the shoe in some such position as shown in Fig. 1 and to catch the end of the shoe proper 11 and the result is that the cross wire is torn down. With the device here shown, however, as the pole strikes the cross wire the shoe is thrown violently counter-clockwise viewing Fig. 1 by the inertia and rebounds so that the rear end of the shoe is elevated and the face forms an approximately smooth line with the front side of the trolley pole over which the cross wire may freely slip. The shock of contact will effect this rebounding action but the braking effect of the washer 23 will retain the shoe in this tilted position without continued oscillation and the cross wire therefore passes freely over the same without damage.

The washer 23 also serves to prevent arcing between the shoe and harp adjacent the pivotal mounting and consequent damage to the harp.

Having thus described in detail the particular form of my invention shown by way of example in the accompanying drawings, of what I claim as new and desire to secure by Letters Patent I shall express in the following claims.

Claims:

1. An overhead device of the class described comprising a sliding contact shoe having a pivotal mounting and brake means to restrain free swinging movement of the shoe.

2. An overhead device of the class de-

scribed comprising a sliding contact shoe having a mounting permitting swinging movement thereof in a vertical plane but serving to hold the shoe in any position to which it may be brought by such movement until acted on by exterior forces.

3. An overhead device of the class described comprising a sliding contact shoe having an extended bearing for contact with the trolley wire pivotally mounted and adapted to be swung to a substantially horizontal position by the pressure of the trolley wire and yieldable means normally serving to maintain the shoe in such position.

4. An overhead device of the class described comprising a harp, a pintle between the arms thereof, a sliding contact shoe on the pintle and a spring washer interposed between an arm of the harp and the shoe to preclude free swinging movement of the latter.

5. An overhead device of the class described comprising a harp, a shoe pivoted between the arms of the harp having a grooved tread portion and a forwardly extending depending bill and means to counteract the overbalancing effect of such bill.

6. An overhead device of the class described comprising a harp, a shoe pivoted between the arms of the harp having a grooved tread portion and a forwardly extending depending bill serving as a guard to prevent the shoe catching over a wire and brake means permitting free pivotal movement of the shoe under the action of an exterior force but tending to hold it in a given position irrespective of the weight of said bill.

In testimony whereof, I have signed my name to this specification.

JOHN L. WHITTAKER.
